UNITED STATES PATENT OFFICE.

CHARLES F. DAMM AND GEORGE HUBER, OF BUFFALO, NEW YORK; SAID HUBER
ASSIGNOR TO SAID DAMM.

VENTILATOR.

1,278,309.

Specification of Letters Patent. Patented Sept. 10, 1918.

Application filed September 1, 1914. Serial No. 859,639.

To all whom it may concern:

Be it known that we, CHARLES F. DAMM and GEORGE HUBER, citizens of the United States, residing at Buffalo, in the county of Erie and State of New York, have invented new and useful Improvements in Ventilators, of which the following is a specification.

This invention relates to a ventilator which is more particularly designed for use on top of the roofs, on the side walls or underneath the floors of cars for ventilating the interior of the same while moving in either direction, although the same may also be used for other purposes.

It is the purpose of this invention to provide a ventilator of this character which is simple and inexpensive in construction, which will permit of effectively ventilating the interior of a car while traveling in either direction or standing still without liability of snow, rain or cinders entering the interior of the car, as well as permitting of regulating the extent of the ventilating effect to meet different requirements, and which can be readily and easily adjusted so that it will operate to ventilate the interior of the car more or less.

In the accompanying drawings:

Figure 1 represents a vertical longitudinal section of one form of our improved ventilator applied to the roof of a railway car. Fig. 2 is a horizontal section thereof, taken in line 2—2, Fig. 1. Fig. 3 is a vertical transverse section taken in line 3—3, Fig. 1. Fig. 4 is a fragmentary vertical longitudinal section showing a slightly modified form of our invention applied either to the floor or side of the car.

Similar characters of reference indicate corresponding parts throughout the several views.

Referring to Figs. 1—3, 1 represents the roof of a car which is assumed to be traveling in the direction of the arrow 2, which is from left to right. 3 represents an upright air flue, preferably of tubular form which is secured in an opening in the roof of the car and communicates at its lower end with the interior of the car while its upper end communicates with the external atmosphere.

4 represents a horizontal hood arranged lengthwise of the car and mounted on top of the roof, preferably by means of flanges 5, 6, depending from opposite longitudinal

sides of the hood and secured to the upper side of the roof of the car. This hood is preferably constructed in the form of a tube which is rectangular in cross section and open at its opposite ends. The upper end of the flue 3 projects through an opening formed centrally in the bottom of the hood, so that this flue extends above this bottom and practically forms an annular upwardly-projecting flange or guard around the central opening in the bottom of the hood.

7, 7 represent two gates or valves which are arranged lengthwise in the hood over the upper end of the flue and have their heels arranged adjacent to each other and preferably hinged or pivoted on a horizontal transverse pintle 8 mounted on the adjacent parts of the longitudinal side walls of the hood, so that both of these gates may be raised and lowered. Each of these gates projects lengthwise of the hood beyond the respective upper end of the flue and provided at its toe or free edge with a downwardly-projecting flange 20 which in the lowest position of the gate is adapted to engage with the bottom of the hood beyond the periphery of the flue. When thus lowered, each gate practically closes or shuts off communication between the upper end of the flue and the respective end of the hood, while upon raising the respective gate more or less, the area of the passageway between this flue and the respective end of the hood may be varied to suit requirements. In its uppermost position, each of the gates is separated from the adjacent part of the top of the hood so as to form a jet passage 9 between these parts.

The raising and lowering of the gates may be variously effected but preferably by the means which are shown in Figs. 1, 2 and 3, and which comprise a vertically-swinging yoke 10 which is of substantially diamond form in a vertical plane and pivoted by means of an ear 11 projecting upwardly from the upper central corner of the yoke and turning upon the central part of the pintle 8 which latter pivotally supports the gates on the hood, thereby permitting the yoke to swing in a vertical plane.

12 represents the vertically-swinging operating or rock lever arranged with its upper part within the flue and pivotally supported between its upper and lower arms on a bracket which is preferably composed of two sections 13, 13 secured to the inner side

of the lower part of the flue. A sliding connection is provided between the upper arm of the operating lever and the yoke by means of a pin 14 arranged horizontally and transversely on the upper arm of the operating lever and passing through a radial slot 15 formed in the yoke adjacent to the lower central corner of the latter. The lower arm of the operating lever is connected with a shipper or shifting rod 16 or other suitable shifting device which may extend to opposite ends of the car within convenient reach of the conductor or motorman, so that the latter may adjust or reverse the ventilator without leaving his post. In the central position of the operating lever, the same stands vertical or nearly so, and at this time the yoke is also arranged in its central position so that neither of the upper edges of the latter which diverge downwardly in opposite directions from the pintle engage with the undersides of the gates whereby both of the latter are permitted to drop by gravity into their lowermost position and engage their toe flanges with the bottom of the hood on opposite sides of the flue and communication between the interior of the car body and the hood is cut off. When it is desired to ventilate the car while the same is traveling from left to right, as indicated by the arrow 2 in Fig. 1, the shipper rod 16 is moved in the direction for causing the operating lever to swing the yoke toward the left. By so doing, the left end of the yoke engages with the underside of the left gate and lifts the same so as to form a passageway which places the upper end of the flue in communication with the left end of the hood, but during this time the right gate is permitted to remain with its toe flange in engagement with the bottom of the hood, so that the right-hand end of the hood is cut off from communication with the upper end of the flue and the interior of the car. When the parts are thus adjusted, the forward movement of the car causes a current of air to pass from right to left through the right-hand end of the hood, thence over the lowered right hand gate, thence over the elevated left hand gate and thence outwardly through the left-hand end of the hood, thereby producing a suction effect upon the upper end of the flue, whereby air from the interior of the car is drawn upwardly through the flue and discharged between the upper end of the latter and the left-hand gate and out through the left-hand end of the hood. This ventilating effect may be varied according to requirements by raising the left gate more or less and is most effective when the left gate is in its highest position in which it is still separated by the comparatively narrow jet passage 9 from the top of the hood through which air may pass from the right to the

left-hand end of the hood, but upon lowering this left gate more or less the area of the outlet passage between the same and the flue is reduced and the ventilating effect is reduced accordingly.

When the car is traveling from right to left, the shifting rod 16 is operated for turning the operating lever and the yoke in the opposite direction for causing the left gate to be lowered upon the bottom of the hood and cutting off communication between the respective end of the hood and the flue, while the right gate is raised more or less for placing the upper end of the flue in communication with the right hand end of the hood. In this reversed position of the parts, a movement of the car from right to left causes a current of external air to pass from left to right through the hood and over the gates, so that the air from the interior of the car is withdrawn by suction through the flue and discharged at the right hand end of the hood.

In order to prevent the gates from being lifted or thrown upwardly into engagement with the top of the hood, and cutting off communication between opposite ends of the hood, and also to prevent rattling or chattering of the gates while elevated into their uppermost position, means are provided which operate to limit the upward movement of the gates and also cause them to bear with a buffing or cushioning effect against the underside of the hood top. The preferred means for this purpose consists in providing each of the gates on its upper side with a button, bumper or stop 17 of rubber or similar elastic material which is adapted to engage with the top of the hood in the highest position of the gate.

In comparatively cold weather, both gates may be lowered upon the bottom of the hood, but during warm weather either one or the other of the gates may be raised so as to produce a withdrawal of the air from the interior of the car. In case the weather is very hot, the gate in the advancing end of the hood may be raised and the gate in the trailing end of the hood may be lowered, in which position of the parts the external air would be caught by the advancing end of the hood and forced downwardly through the flue into the interior of the car, thereby aiding in cooling the same.

The bottom of the hood 4 preferably inclines from opposite sides of the flue 3 toward opposite ends of the hood so that this bottom will shed to the exterior any water which may fall on the same. In order to form a good joint between the gates and the bottom of the hood when either gate is closed the oppositely inclined parts of the bottom are provided with outwardly facing shoulders 21 each of which is overlapped by the flange 20 of the respective gate when

the latter is fully lowered, as shown for instance at the right of Fig. 1.

Rain, snow and cinders are prevented from entering the car through the hood and flue by means of louvers, or slats 22 which are arranged transversely in opposite ends of the hood and incline outwardly, as shown in Figs. 1 and 2, so as to form guards or baffles which deflect any rain, snow or cinders downwardly away from the hood but permitting the air to enter and leave the hood freely. The opposite ends of the hood bottom also preferably terminate short of the outer edges of the lowermost guard slots, as shown in Fig. 1, so as to prevent rain, snow or cinders from striking the same and entering the hood.

By extending the upper end of the flue above the bottom of the hood, a guard flange is produced which aids in preventing the entrance of rain, snow or cinders from the exterior of the car through the hood and into the interior thereof.

When our improved ventilator is employed on the roof of the car the weight of the gates may be relied upon to hold the same normally in a closed position, but when this ventilator is employed on the side of a car or underneath the bottom thereof, the force of gravity cannot be utilized to hold the gates normally in their closed position. When, therefore, the ventilator is applied either to the side wall or to the bottom of a car, which is represented by 18 in Fig. 4, the gates may be yieldingly held in their closed position by means of springs 19 interposed between the outer side of the gate and the outer side of the hood.

It will be apparent that this ventilator is very compact in construction, it can be easily applied to cars of standard construction without detracting from the external or internal appearance of the same, and the same

permits of effectively withdrawing the air from the car or injecting air into the same as well as regulating the amount of air thus supplied to or withdrawn from the car.

We claim as our invention:

1. A ventilator, comprising a flue, two gates pivotally supported independently of each other over said flue, and means for opening and closing said gates comprising a movable yoke adapted to engage with either one or the other of said gates and movable independently of both of said gates. 55

2. A ventilator, comprising a tubular hood which is open at its opposite ends, a flue communicating with the central part of said hood, two independently movable gates arranged within said hood over said flue and having their heels pivotally supported adjacent to each other while their toes normally engage edgewise with the bottom of said hood on opposite sides of said flue, and means for turning said gates independently 60 of each other.

3. A ventilator comprising a tubular hood which is open at its opposite ends, a flue communicating with the central part of said hood, two independently movable gates arranged within said hood over said flue and having their heels arranged adjacent to each other while their toes are movable toward and from the bottom of the hood on opposite sides of said flue, a pintle which is 75 mounted on said hood and on which the heels of said gates are pivoted independently of each other, and means for turning said gates.

Witness our hands this 29th day of 80
August, 1914.

CHARLES F. DAMM.
GEORGE HUBER.
